UNITED STATES PATENT OFFICE.

CARL J. ANDERSON, OF CHICAGO, ILLINOIS, ASSIGNOR, BY DIRECT AND MESNE ASSIGNMENTS, OF ONE-THIRD TO RICHARD HOLM AND ONE-THIRD TO ERIK BORG, BOTH OF CHICAGO, ILLINOIS.

MANUALLY-GUIDED MOTOR-DRIVEN ABRADING MACHINE.

Application filed December 21, 1925. Serial No. 76,578.

The embodiment herein shown of the invention is in the form of an implement especially designed for use in abrading the upper surface of butchers' blocks for the purpose of producing a smooth, clean surface thereon. Among the salient objects of the invention as applied to such use are, to attain a high degree of convenience in operation, to provide an adjustable mounting for the rotary abrading element to compensate for wear, and to provide resilient means for lifting the apparatus so as to remove the abrading element from contact with the surface upon which the apparatus rests when the operator releases the apparatus.

The invention may also be embodied in apparatus especially adapted for use in abrading or polishing floors and the like.

In the accompanying drawings, Figure 1 is a side view of an apparatus embodying the features of my invention with certain parts broken away.

Fig. 2 is a plan view with the side cover plate in section to disclose a certain gear train.

Fig. 3 is a sectional view taken in the plane indicated by dotted line 3-3 of Fig. 4 and dotted line 3-3 of Fig. 2.

Fig. 4 is a section on line 4-4 of Fig. 3.

Figs. 5 and 6 are detail views of certain parts comprised in the rotary abrading element.

In the drawings, A denotes a butcher's block or the like which is to be resurfaced.

The apparatus comprises a casing 1 which may be a casting, said casing being provided with a hand-hold 2 at its forward end and a handle 3 at its rear end. The forward end of the casing 1 is adapted to rest upon the surface to be treated. The rear end of the casing is supported by resilient means consisting of a relatively wide roller 4, the ends of which are journaled in plungers 5, only one of which is shown in the present drawings. Each plunger is mounted in a vertically extending recess 6 in the rear end of the casing 1 and is urged downwardly by a coiled expansive spring 7 mounted within said recess, as shown in Fig. 1. The extent of movement of the plunger 5 under the action of the spring 7 is limited by contact of a nut 8 on the upper end of said plunger with a stop surface 9.

The abrading element may be described

as a rotary brush and is designated by the reference number 10 (Figs. 3 and 4). Said brush preferably consists of a multiplicity of circumferential series of spring steel members 11 radiating from a central shaft 12. Surrounding the shaft 12 and secured thereto by means of set screws 13 is a sleeve 14. Each spring-steel brush element 11 is of V-shape and is secured to the sleeve 14 by means including pins 15 which lie within the angles of the V-shaped brush elements 11 and extend through holes 16 formed in washers 17 (Fig. 5) which fit upon the sleeve 14 and alternate with the circumferential series of brush elements. The washers 17 and the brush elements held therebetween are clamped together by means of two end locking washers 18 (Fig. 6) having non-circular apertures 19 to correspond with the form of the ends of the sleeve 14. The locking washers 18 are drawn together by means of tie rods 20 and nuts 21 on the ends of said tie rods. As shown in Fig. 5 the washers 17 are notched as at 22 to accommodate the tie rods 20, whereby said tie rods serve to prevent the washers 17 and the brush elements from turning upon the sleeve 14.

As shown in Fig. 3, the arms of each V-shaped spring bear against the arms of the next adjacent spring, whereby each spring supports the adjacent springs and cooperates with them to restore the springs to substantially radial position after the springs have been flexed through contact with the work.

The shaft 12 is mounted in roller bearings 23 carried by the ends of a yoke 24 which is pivotally supported within the casing 1 by means of a shaft 25. The yoke 24 is provided with a gear segment 26 adapted to mesh with a pinion 27 which is fixed upon a shaft 28 journaled in the upper part of the casing 1. Upon one end of the shaft 28 outside of the casing is a knurled knob 29 by means of which the pinion 27 may be manually rotated to swing the yoke 24 to compensate for wear of the ends of the springs 11, and to cause the brush to project to a greater or less extent from the open lower side of the casing 1. 30 is a clamping nut on one end of the shaft 28 which may be tightened up to lock the yoke 24 in adjusted position.

The means for rotating the brush in the direction shown by the arrow in Fig. 3 comprises an electric motor 31 located within a compartment 1^a in the forward part of the 5 casing 1 and separated from that part of the casing which contains the segment 24 and the brush 10 by means of a partition 32. In one side wall of the compartment 1^a is an opening for the introduction of the 10 motor, said opening being closed by a plate 1^b which also forms part of the means for supporting the motor. On one end of the motor shaft is a pinion 33 (Fig. 2) meshing with a spur gear wheel 34 which is mounted 15 to rotate upon the axis of the shaft 25. Rigid with the gear wheel 34 is a pinion 35 that meshes with an idler or intermediate gear 36 which in turn meshes with a pinion 37 which is rigidly secured to one end of the 20 brush shaft 12. The gear train just described is located outside the main casing 1 and is enclosed by a cover plate 38 detachably secured to one side of the main casing 1. The gear wheel 36 is mounted on 25 a stud 39 (Fig. 3) which is carried by the yoke 24 and projects through an arc-shaped slot 40 in one side of the main casing 1.

Electric current is conveyed to the motor 31 in any preferred manner, as for example, 30 by means of an electric cord (not shown) having a plug adapted to fit in the receptacle 41 (Fig. 2) carried by the main casing 1. 42 indicates a switch for controlling the supply of current to the motor.

35 Within the lower forward portion of the chamber in which the brush is located is a dust receptacle (see Fig. 3) comprising a bottom 43, two sides 44 and an end wall 45. The dust receptacle is pivoted upon the axis 40 46. Normally the bottom of the dust receptacle is approximately flush with the lower side of the main casing 1 and extends to a point close to the brush. The dust receptacle is yieldingly held in such position by 45 means of a spring arm 47 secured within the brush chamber in any preferred manner. The spring arm 47 has a V-shaped portion 48 into which the upper edge of the end wall 45 of the dust receptacle is adapted to snap 50 when the operator swings the dust receptacle down against the tension of the spring 47 to dump the contents of the receptacle. The spring arm 47 thus serves to hold the dust receptacle in dumping position. When 55 the receptacle is pushed back to normal position the spring arm 47 serves to secure it in such position.

In use, the operator bears down on the 60 handle 3 sufficiently to bring the rapidly revolving brush into contact with the work. The operator pushes the apparatus back and forth over the surface to be treated, the rapidly rotating springs 11 serving to abrade the surface. As will be evident 65 from the drawings, the casing 1, the sup-

porting roller 4 and the brush 10 are sufficiently wide so that the apparatus may be moved along the outer portion of the surface of the butcher's block being treated, so as to enable the brush to operate across the 70 entire top of the block and out to the edges of the latter. When the operator relieves the pressure upon the handle 3 the springs 7 lift the rear end of the casing 1 sufficiently to remove the brush from the surface being 75 treated, thereby preventing the apparatus from running off the block in case the operator releases the apparatus without first stopping the motor.

The metallic brush or abrading element 80 herein shown is well adapted for abrading or surfacing floors and the like. Hence I would have it understood that the claims hereinafter set forth in regard to the brush are not to be limited to an apparatus for 85 resurfacing butchers' blocks.

I claim as my invention:

1. A rotary abrading element comprising a central support, a plurality of circumferential series of V-shaped springs, the 90 free ends of the arms of each spring bearing against the arms of the adjacent springs, and means for securing the springs to the central support comprising pins extending 95 parallel with the central support and lying within the angles of the V-shaped springs, spacing washers surrounding the central support and alternating with the circumferential series of springs, said pins extending 100 through said washers, two end locking washers at opposite ends of the series of springs and spacing washers, and tie rods for drawing the locking washers together to clamp the springs and the spacing washers 105 together.

2. A rotary abrading element comprising a central support, a plurality of circumferential series of V-shaped springs, the free ends of the arms of each spring bearing against the arms of the adjacent springs, and means for securing the springs to the central support comprising pins extending parallel with the central support and lying within the angles of the V-shaped springs, spacing washers surrounding the central 110 support and alternating with the circumferential series of springs, said pins extending through said washers, and means to clamp the springs and the spacing washers together.

3. A rotary abrading element comprising a central support, a circumferential series of V-shaped springs, the free ends of the arms of each spring bearing against the arms of the adjacent spring, and means for securing the springs to the central support comprising pins extending parallel with the central support and lying within the angles of the V-shaped springs, and means to secure 115 the pins to the central support.

4. A rotary abrading element comprising a central support and a circumferential series of V-shaped springs connected adjacent to the angles of the springs to said central support, the free ends of the arms of each spring bearing against the arms of the adjacent springs whereby each spring supports the adjacent spring and cooperates with them to restore the springs to substantially radial position after the springs have been flexed through contact with the work.
5. A manually-guided motor-driven abrading machine comprising, in combination, a casing adapted to slide upon a surface to be abraded, said casing having a forward motor compartment and a rear brush compartment, an electric motor in said motor compartment, a pivoted support within the brush compartment, a rotary brush carried by said support, a pivoted dust receptacle within the brush compartment adjacent to the periphery of the brush, a driving connection between said motor and brush comprising a gear train extending outside of said compartments and including a gear mounted coaxially with the pivot of said support, a handle on the casing adjacent to the brush and a resilient support for said casing adjacent to the brush for lifting the casing sufficiently to remove the brush from contact with the sustaining surface when the operator relieves the pressure upon the handle.
15. In testimony whereof, I have hereunto affixed my signature.

CARL J. ANDERSON.
